H. A. SCHERMERHORN.
WIRE SPLICER.
APPLICATION FILED DEC. 18, 1908.

923,586.

Patented June 1, 1909.

UNITED STATES PATENT OFFICE.

HERSCHEL A. SCHERMERHORN, OF SHABBONA GROVE, ILLINOIS.

WIRE-SPlicer.

No. 923,586.

Specification of Letters Patent. Patented June 1, 1909.

Application filed December 18, 1908. Serial No. 468,093.

To all whom it may concern:

Be it known that I, HERSCHEL A. SCHERMERHORN, a citizen of the United States, residing at Shabbona Grove, in the county of Dekalb and State of Illinois, have invented certain new and useful Improvements in Wire-Splacers, of which the following is a specification.

This invention relates to improvements in a tool or utensil to be used for splicing the wires of wire-fences, and it consists in certain peculiarities of the construction, novel arrangement, and operation of the various parts thereof, as will be hereinafter more fully set forth and specifically claimed.

The principal object of the invention is to provide an implement which is primarily intended for splicing or mending the broken wires of wire-fences in a quicker, cheaper and more effective way than ordinarily, yet may also be used for tightening the slack strands of wires of either barbed-wire or woven-wire fences.

Other objects and advantages of the invention will be disclosed in the subjoined description and explanation.

In order to enable others skilled in the art to which my invention pertains, to make and use the same, I will now proceed to describe it, referring to the accompanying drawing, in which—

Figure 1 is a view in elevation of a wire-splicer embodying one form of the invention, showing the parts thereof by continuous lines in the positions they will occupy when being used as a splicer, as well as a tightener, and by dotted lines the positions to which the members of the split shaft may be placed when the tightening jaws are disengaged from the wire; Fig. 2 is a plan view of a broken wire showing the tool and splice wire in their initial positions in the operation of splicing a broken wire; Fig. 3 is a similar view of like parts, showing the tool after it has been turned so as to wind up the splice-wire thereon; Fig. 4 is a like view of a part of the tool as employed in fastening the splice-wire to the main wire; Fig. 5 is a cross-sectional view taken on line 5—5 of Fig. 1 looking in the direction indicated by the arrows; and Fig. 6 is a view in elevation of a modified form of the splicer.

Like numerals of reference, refer to corresponding parts throughout the different views of the drawing.

The reference numeral 10 designates the

split shaft of the tool which is shown in Figs. 1 to 5, inclusive, as consisting of two members 11 pivotally secured together near one of their ends by means of a bolt or rivet-pin 12, so that they may be folded together as shown by full lines in said views, thus forming a split-shaft substantially rectangular in cross-section throughout the major part of its length. Each of the members 11 is provided at one of its ends, which I will term its front end, with a jaw 13 spirally in shape like the bit of an auger, and each of said jaws is provided on its inner portion with a rounded projection 14 which, when the members 11 are closed together, will impinge against one another and provide an opening 15 between said projections and the front surfaces of the jaws 13 for the reception of a wire which it may be desired to tighten, which may be done by turning the tool in either direction, in which operation it is apparent that the wire will be bent around both of the projections 14, thus taking up the slack of the wire, when by separating the members 11 the projections 14 may be removed from the loop or twist formed by the jaws 13 and said projections thereon. Each of the members 11 is provided at a short distance rearwardly from the pivot 12 thereof with an opening 16 for the reception of the splice-wire 17, and said openings will register with one another when the members 11 are folded together as is apparent. At its rear end each of the members 11 is provided with a rectangular tapered portion 17 to fit in a tapered socket 18 formed in one end of a crank-handle 19 which is used for turning the tool either in the operation of splicing or in the operation of tightening the slack wire.

As is clearly shown in the different views of the drawings the split-shaft 10 is enlarged from a point as at 20 slightly rearward of the openings 16 therein toward its front end, thereby affording greater strength at the points requiring the same. From a point a slight distance rearwardly of the openings 16 in the members 11 of the split-shaft said members are formed substantially rectangular in cross-section and taper slightly toward their rear ends, as is clearly shown. This feature of forming the shaft 10 substantially rectangular in cross-section so that the main portion of the splicing wire may be wound on said part of the shaft is very important, as I have found by practice and use that when a cylindrical shaft is employed for

winding the splicing wire on the same the said wire will recoil, whereas by using the rectangular shaped shaft the recoil of the wire will be prevented.

5 In Fig. 6 of the drawing I have shown a modification in the construction of the tool or device which consists in providing a shaft 10^a of a single piece of material and in omitting the clamping-jaws 13 and pivot-pin, as 10 it is obvious that the latter will not be required unless the shaft is composed of two separable members. In this modification the shaft 10^a is provided with an opening 16 near its front end, and from a suitable point 15 slightly to the rear of said opening the shaft 10^a is formed substantially rectangular in cross-section and tapered toward its rear end, and, as in the other construction, is provided with a rectangular tapered portion 17 20 to fit in the socket of the crank-handle.

The operation of the device in tightening slack wires has been above explained, and is of secondary importance in this present invention.

25 In order to splice a broken wire (see Figs. 2 to 4 inclusive) a splice-wire 17^a is looped through a loop 21 on one end of the main wire 22, and then both strands of the splice-wire 17^a are passed through a loop 23 30 formed on the other section of the main wire 22, and then through the openings 16 in the shaft of the tool. By placing the crank-handle 19 on the rear end of the tool and turning the same thereby or otherwise, it is 35 apparent that the splice-wire 17^a will be wound around the substantially rectangular portion of the shaft of the tool, as is clearly shown in Fig. 3 of the drawing, in which view it will be observed that in the beginning 40 of the winding of the splice-wire but a small portion thereof will lie on the rounded portion 20^a of the shaft while the greater portion

of the splice-wire will be wound around the substantially rectangular portion of the shaft of the tool. When thus wound the shaft of 45 the tool may be advanced toward the loop 21 and passed around the splice-wire 17^a near the loop 23, which operation will unwind that portion of the wire 17^a from the shaft of the tool which has been wound 50 therearound and twist or wind it around the splice-wire between the loops 21 and 23 of the sections of the main wire, as is clearly shown in Fig. 4 of the drawing, after which the stem 55 of the tool may be withdrawn from the splice-wire, thus leaving the sections of the broken wire firmly united.

Having thus fully described my invention, what I claim as new, and desire to secure by Letters-Patent, is—

60 1. A wire-splicer consisting of a split-shaft comprising two members pivotally secured together near their ends and each having its major portion formed substantially rectangular in cross-section and provided with an opening intermediate of their ends for the reception of a splicing-wire, and detached means to engage both of said members when closed for the purpose of turning the shaft.

65 2. A wire-splicer consisting of a shaft comprising two members pivotally secured together near their ends and each having its major part formed substantially rectangular in cross-section and each provided with an opening intermediate of its ends to register 70 with one another and for the reception of a splicing-wire, and a crank-handle having a socket in one of its ends to engage one end of the shaft.
